UNITED STATES PATENT OFFICE.

HARRY K. SMITH, OF BALTIMORE, MARYLAND.

METHOD AND MACHINE FOR MAKING BLANKS FROM A SHEET.

Application filed January 26, 1925. Serial No. 4,934.

My invention relates to a method and machine for making blanks from a sheet.

Among the objects of my invention are:—

To devise a method for increasing the production of blanks, formed from a sheet, particularly sheet metal blanks, and for decreasing the amount of manual labor involved in said production.

To produce a unitary machine for the making of blanks from sheet material, including metal.

My invention comprehends, in its special phase, the producing of a single machine which shall perform the trimming and slitting operations in the manufacture of sheet metal blanks. As now accomplished, sheets of tin or other metal are fed from stacks to trimming machines which cut and trim the same into two blanks, the width of each blank being equal to one dimension of the proposed blank. These blanks are stacked as they come from the trimmer and are then manually fed to the slitting machine which cuts the same at right angles to their length, thus sizing the blank. This method entails considerable handling of the material and especially requires great skill in the feeding of the blanks to the machines.

Other methods have been devised in which the blanks, after passing through the trimmer, are carried by means of a conveyor to the slitter. Owing to the fact that the trimmer cuts two blanks, this method slows down production because of the necessity for retarding the movement of one blank while the other is being fed to the slitter.

My improved method and machine overcome these difficulties by requiring a minimum of hand labor and by providing a continuous and uniform flow of the sheet material, thereby insuring a maximum rate of production.

In the drawings:—

Figure 1 is a plan view of my improved machine, certain of the under parts thereof being omitted.

Fig. 2 is a view looking in the direction of the arrow 2 in Fig. 1, showing the trimming portion of my improved machine.

Fig. 3 is a view looking in the direction of the arrow 3, showing the relation of the cutting rollers hereinafter described.

Fig. 4 is a section along the line 4—4 in Fig. 1 looking in the direction of the arrows.

Fig. 5 is a section along the line 5—5 in Fig. 4 looking in the direction of the arrows, certain of the parts being omitted.

Fig. 6 is a view of a portion of the machine looking in the direction of the arrow 6 in Fig. 1, showing the relation of certain parts hereinafter described.

In the drawings:—

10 is the bed of my improved machine which is provided with a table 11 for the reception of the metallic sheets. A guide 12 is laterally adjusted in slots such as 13 formed in the table 11, said guide serving to position the sheet on its way to the rollers hereinafter described.

Bearing blocks such as 14 are formed on each side of the table 11 adjacent the delivery end thereof, and a shaft 15 is revolvably mounted in said bearings. Cutting rolls such as 16 are adjustably secured to the shaft 15 by set screws such as 17.

The shaft 15 extends through both blocks 14 and on the right end thereof, as viewed in Fig. 1, said shaft has secured thereto the spur gear 18 and the bevel gear 19. On the left end of said shaft is secured the bevel gear 20. Shoulders formed on the gears 18 and 20, respectively, prevent endwise movement of the shaft 15. The spur gear 18 meshes with the spur gear 21 which is secured on the shaft 22 revolvably mounted in the side frames 23 directly beneath the shaft 15.

The shaft 22 extends to the right, as viewed in Fig. 1, and is attached to any suitable source of power, not shown, for driving my improved machine.

On that portion of the shaft 22 within the side frames 23, a plurality of cutting rolls such as 24 is adjustably secured by set screws such as 25. The cutting rolls 16 and 25 are positioned with reference to each other as shown in Fig. 3 and operate to cut metallic sheets passed therebetween in a manner which is well-known in the art and which forms no part of my invention.

The rolls 16 and 25 perform the trimming operation in the making of the sheet metal blanks, the central pair of rolls cutting in half the metallic sheets passed therethrough and the end pairs of rolls trimming the edges of said sheet, the distance between the cutting edges of the central pair of rolls and those of any end pair determining one dimension of the proposed blank.

The bevel gear 19 meshes with the bevel gear 26 secured on the shaft 27 which is revolvably mounted in bearing blocks such as 28 formed on the frame of the machine. At 5 the other end of the shaft 15 the bevel gear 20 meshes with the bevel gear 29 secured on the shaft 30 which is revolvably mounted in bearing blocks such as 31 formed on the frame of the machine. The shafts 15, 27 10 and 30 lie in the same horizontal plane, with the latter two shafts at right angles to and on the same side of the first-named shaft. Adjustably secured to the shaft 27 between the blocks 28 by set screws such as 72 is a 15 plurality of cutting rolls such as 32. Similarly, between the bearing blocks 31, a plurality of cutting rolls such as 33 is adjustably secured to the shaft 30 by set screws such as 73. Directly beneath the shaft 27 20 a shaft 34 is revolvably mounted in the frames 23 and directly beneath the shaft 30, a shaft 35 is revolvably mounted in said frames.

The shaft 34 has secured thereto the spur gear 36 which meshes with the spur gear 37 secured to the shaft 27. Similarly, to the shaft 35 the spur gear 38 is secured which meshes with the spur gear 39 secured to the shaft 30.

30 A plurality of cutting rolls such as 40 is adjustably secured to the shaft 34 between the side frames 23 by set screws such as 74, each of said rolls being positioned to operate in the usual way with a roll 32 on the shaft 27.

35 A plurality of cutting rolls such as 41 is adjustably secured on the shaft 35 between the side frames 23 by set screws such as 75, each of said rolls being positioned to operate in the usual way with a roll 33 secured to the upper shaft 30.

40 Endwise movement of the shafts 27 and 34 is prevented by shoulders formed on the gears 37 and 36, respectively, and by collars 45 such as 76 secured to the other ends of said shafts. Similar provision is made for the shafts 30 and 35 by shoulders on the gears 39 and 38, respectively, and collars such as 77 secured to the opposite ends of said shafts.

50 The cutting rolls 32 and 40, respectively, and 33 and 41, respectively, perform the slitting operation in my improved machine, each of said pairs of rolls being positioned along 55 their respective shafts so that the distance between their cutting edges determines one dimension of the proposed blank.

55 After the metallic sheet has been cut into two smaller sheets by the interaction of the rolls 16 and 24, the latter sheets are delivered by the momentum imparted to them by said rolls to a platform 42, which is lower than the table 11, (see Fig. 6), for a purpose 60 hereinafter explained. The platform 42 is 65 provided with grooves such as 43 substan-

tially parallel to the shaft 15, and shoes such as 44 and 68 are adapted to slide freely within each of said grooves.

A reciprocating rib 45 is secured to the shoes 44, the end of said rib opposite the trimming rolls having formed integrally therewith and at right angles thereto a stop 46, for a purpose hereinafter explained. The rib 45 has one of its top edges chamfered, as shown in Figs. 4 and 6, to form the feather edge 47, for a purpose hereinafter explained. A similar rib 66 provided with a stop 67 is secured to the shoes 68 and said rib is chamfered at the upper portion thereof to form the feather edge 69, for a purpose hereinafter explained. When said ribs and stops are in the position to receive the metallic sheets from the cutting rolls 16 and 25, as in Fig. 1, said ribs are in contact throughout their length and present the appearance of a T. The ribs 45 and 66, by reason of their being secured to the shoes 44 and 68, respectively, may slide freely to and fro upon the surface of the platform 42, and the mechanism by which this reciprocating motion is obtained will now be described:—

As this mechanism is the same for the rib 45 which moves toward the shaft 27 as for the rib 66 which moves toward the shaft 30, but one set of the same, that for the rib 66, will be described.

Revolvably mounted in the frame 23 of the machine is the shaft 48 which is provided on its outer end with a spur gear 49 meshing with the spur gear 38. The shaft 48 extends through the side frame 23 and on its inner end has secured thereto a cam 50 which is provided with the groove 51. A roller 52 cooperates with the groove 51 and said roller is mounted in one end of the lever 53, the other end of said lever being revolvably mounted on the rock shaft 54 secured in the side frame 23. The end of the lever 53, to which the roller 52 is secured, has also pivotally secured thereto one end of a link 55, the other end of said link being pivotally secured to the lever 56 at a point intermediate of the ends of said lever. One end of the lever 56 is revolvably mounted on the rock shaft 57 secured in the frame 23 and the other end of said lever has pivotally secured thereto one end of the link 58, the other end of said link being pivotally secured to a rod 58^a, the ends of which are mounted in the depending ears 59 formed on the shoes 68. The ears 59 slide freely in the slots 60 formed in the platform 42 and said slots are aligned with the grooves 43 hereinbefore described.

Flat springs, such as 61, having one end 125 curled such as 62 are secured to a bar 63 which is mounted on the bearing blocks 14. Similar springs such as 64 are mounted on bars such as 65 which are secured to the bearing blocks 28 and 31, respectively. The 130

curled ends 62 of the springs 61 contact with the table 11 and those of the springs 64 contact with the platform 42 and serve to prevent the buckling of the sheet of metal 5 on its way to the cutting rolls.

The operation of my improved machine will now be described:—

The spacing of the cutting rolls 16 and 24, respectively, 32 and 40, respectively, 41 and 33, respectively, having been determined, the operator places a sheet of metal on the table 11 and moves the same toward the rolls 16 and 24. The interaction of these rolls cuts the sheet into two parts and trims the two edges at right angles to the shaft 15. The two parts heretofore mentioned are then moved across the platform 42 by the momentum imparted thereto by the rolls 16 and 24 and the leading edges of the two sheets contact with the stops 46 and 67. During this movement, said sheets are separated by the feather edges 47 and 69 of the ribs 45 and 66, respectively. Since these ribs are in contact throughout their lengths, the edges 47 and 69 practically form one edge. The two parts of the sheet metal are now in position to be moved to the slitting rolls, which is accomplished by the groove 51 of the cam 50 cooperating with the roller 52, this motion being translated through the links and levers hereinbefore described to the ribs 45 and 66. When the roller 52 dwells in the portion 70 of the cam groove 51, the ribs 45 and 46 are in position for the reception of the metallic sheets, as shown in Fig. 1, but when in the rotation of the cam 50 the roller 52 reaches the portion 71 of the cam groove 51, the rib 47 is moved toward the shaft 27 and the rib 66 is moved toward the shaft 30, thus moving the respective sheets of metal toward the slitting rolls.

My improved machine, therefore, provides a continuous flow of material from the time it is inserted between the trimming rolls until it issues from the slitting rolls as properly sized can blanks.

Each of the sheets issuing from the trimming rolls is cut simultaneously so that retardation of one of the sheets is not required, 50 nor is manual labor necessary in order to move the trimmed sheets to the slitting rolls.

While I have shown one preferred form of my invention, it is to be understood that this is for the purpose of illustration only and 55 in no-wise to limit the scope thereof, for many changes may be made in my invention without departing from the spirit thereof.

I claim:—

1. The herein described method of making 60 blanks from a sheet, which consists in cutting said sheet into a plurality of smaller sheets, moving said smaller sheets in opposite directions at right angles to the direction of receipt from the cutting rolls and then

cutting said smaller sheets into a plurality 65 of blanks.

2. The herein described method of making blanks from a sheet, which consists in cutting said sheet into a plurality of smaller sheets, separating and simultaneously cutting 70 said smaller sheets into a plurality of blanks.

3. The herein described method of making blanks from a sheet, which consists in cutting said sheet into a plurality of smaller 75 sheets, moving said smaller sheets at right angles to the direction of receipt from the cutting rolls and then simultaneously cutting said smaller sheets into a plurality of blanks.

4. The herein described method of making blanks from a sheet, which consists in cutting said sheet into a plurality of smaller sheets, separating and moving said smaller sheets at right angles to the direction of 85 receipt from the cutting rolls and then simultaneously cutting said smaller sheets into a plurality of blanks.

5. The herein described method of making blanks from a sheet, which consists in cutting said sheet into a plurality of smaller sheets, moving said smaller sheets in opposite directions and then cutting said smaller sheets into a plurality of blanks.

6. The herein described method of making blanks from a sheet, which consists in cutting said sheet into a plurality of smaller sheets, moving said smaller sheets in opposite directions and then simultaneously cutting 95 said smaller sheets into a plurality of 100 blanks.

7. The herein described method of making blanks from a sheet, which consists in cutting said sheet into a plurality of smaller sheets, simultaneously separating and simultaneously cutting said smaller sheets into a 105 plurality of blanks.

8. The herein described method of making blanks from a sheet, which consists in cutting said sheet into a plurality of smaller sheets, separating and moving said smaller sheets in opposite directions at right angles to the direction of receipt from the cutting rolls and then cutting said smaller sheets 110 into a plurality of blanks.

9. The herein described method of making blanks from a sheet, which consists in cutting said sheet into a plurality of smaller sheets, moving said smaller sheets in opposite directions at right angles to the direction of receipt from the cutting rolls and then simultaneously cutting said smaller sheets 120 into a plurality of blanks.

10. The herein described method of making blanks from a sheet, which consists in cutting said sheet into a plurality of smaller sheets, separating and moving said smaller sheets in opposite directions and then cutting 125

said smaller sheets into a plurality of blanks.

11. The herein described method of making blanks from a sheet, which consists in cutting said sheet into a plurality of smaller sheets, separating and moving said smaller sheets in opposite directions and then simultaneously cutting said smaller sheets into a plurality of blanks.

12. The herein described method of making blanks from a sheet, which consists in cutting said sheet into a plurality of smaller sheets, simultaneously separating and moving said smaller sheets in opposite directions and then cutting said smaller sheets into a plurality of blanks.

13. The herein described method of making blanks from a sheet, which consists in cutting said sheet into a plurality of smaller sheets, simultaneously separating and moving said smaller sheets in opposite directions and then simultaneously cutting said smaller sheets into a plurality of blanks.

14. In a machine for making blanks from a sheet, the combination with means for cutting said sheet into a plurality of smaller sheets, of blank cutting rolls, and means for separating and simultaneously feeding said smaller sheets to said rolls.

15. In a machine for making blanks from a sheet, the combination with means for cutting said sheet into a plurality of smaller sheets, of blank cutting rolls, and means for simultaneously feeding said smaller sheets to said rolls.

16. In a machine for making blanks from a sheet, the combination with means for cutting said sheet into a plurality of smaller sheets, of means for simultaneously cutting said smaller sheets into blanks.

17. In a machine for making blanks from a sheet, the combination with means for cutting said sheet into a plurality of smaller sheets, of means for simultaneously cutting said smaller sheets into blanks and means for feeding said sheets to said second named means.

18. In a machine for making blanks from a sheet, the combination with means for cutting said sheet into a plurality of smaller sheets, of means for simultaneously cutting said smaller sheets into blanks, and means for separating and feeding said sheets to said second named means.

19. In a machine for making blanks from a sheet, the combination with means for cutting said sheet into a plurality of smaller sheets, of means for simultaneously cutting said smaller sheets into blanks, and means for separating and simultaneously feeding said sheets to said second named means.

20. In a machine for making blanks from a sheet, the combination with means for cutting said sheet into a plurality of smaller sheets, of means for simultaneously cutting said smaller sheets into blanks, and

means for simultaneously feeding said sheets to said second named means.

21. In a machine for making blanks from a sheet, the combination with means for cutting said sheet into a plurality of smaller sheets, of means for cutting said smaller sheets into blanks and means for simultaneously feeding said sheets to said second named means.

22. In a machine for making blanks from a sheet, the combination with means for cutting said sheet into a plurality of smaller sheets, of means for simultaneously cutting said smaller sheets into blanks, and means for simultaneously separating and feeding said sheets to said second named means.

23. In a machine for making blanks from a sheet, the combination with means for cutting said sheet into a plurality of smaller sheets, of means for cutting said smaller sheets into blanks, and means for simultaneously separating and feeding said sheets to said second named means.

24. In a machine for making blanks from a sheet, the combination with means for cutting said sheet into a plurality of smaller sheets, of means for simultaneously separating said smaller sheets, means for simultaneously cutting said sheets into blanks and means for simultaneously feeding said sheets to said second named means.

25. In a machine for making blanks from a sheet, the combination with means for cutting said sheet into a plurality of smaller sheets, of means for simultaneously cutting said smaller sheets into blanks, said last named means being spaced apart and substantially parallel to the direction of delivery from said first named cutting means.

26. In a machine for making blanks from a sheet, the combination with means for cutting said sheet into a plurality of smaller sheets, of blank cutting rolls for simultaneously cutting said smaller sheets into blanks, said rolls being spaced apart and substantially parallel to the direction of delivery from said cutting means, and means for simultaneously feeding said smaller sheets to said rolls.

27. In a machine for making blanks from a sheet, the combination with means for cutting said sheet into a plurality of smaller sheets, of blank cutting rolls for simultaneously cutting said smaller sheets into blanks, said rolls being spaced apart and substantially parallel to the direction of delivery from said first named cutting means, and means adapted to move said smaller sheets in opposite directions towards said rolls.

28. In a machine for making blanks from a sheet, the combination with means for cutting said sheet into a plurality of smaller sheets, of blank cutting rolls for simultaneously cutting said smaller sheets into blanks, said rolls being spaced apart and substan-

tially parallel to the direction of delivery from said cutting means, and means for separating and simultaneously feeding said smaller sheets to said rolls.

5 29. In a machine for making blanks from a sheet, the combination with means for cutting said sheet into a plurality of smaller sheets, of blank cutting rolls for simultaneously cutting said smaller sheets into blanks,

said rolls being spaced apart and substantially parallel to the direction of delivery from said first named cutting means, and means adapted to separate and move said smaller sheets in opposite directions towards said rolls.

In testimony whereof, I affix my signature.

HARRY K. SMITH.
